UNITED STATES PATENT OFFICE.

JOSEPH L. HOFFMAN, OF PORTLAND, OREGON.

AUTOMATIC FEED CONTROL FOR OIL-BURNERS.

1,314,807.

Specification of Letters Patent.

Patented Sept. 2, 1919.

Application filed June 13, 1916. Serial No. 103,594.

To all whom it may concern:

Be it known that I, JOSEPH L. HOFFMAN, a citizen of the United States, residing in the city of Portland, county of Multnomah, 5 and State of Oregon, have invented certain new and useful Improvements in Automatic Feed Controls for Oil-Burners, of which the following is a specification.

My invention relates to automatic feed 10 control for oil burners, and has for its principal object to provide a device which will operate automatically, under the control of the boiler pressure, for controlling the steam and oil supply to the oil burner.

Another object is to provide a device of 15 simple and practical construction and which can be easily adjusted for the purpose of regulating the admission of steam, or the admission of oil, or both, to the burner, as 20 high efficiency may require.

A still further object of the invention is to provide a simple connection whereby steam can be discharged through the oil 25 burner, at will, for cleaning the same.

In order that others may understand my 30 invention, I have illustrated one practical embodiment thereof on the inclosed sheet of drawing which I will now describe.

The figure shows a vertical sectional view 35 of one practical embodiment of my invention, the oil burner being shown in elevation with a portion of the connections thereto broken out to reduce the size of the figure.

Referring now more in detail to the drawing, the invention, as here illustrated, comprises a main body 1, having therein, at its upper end, a steam chamber 2, to which steam is admitted from the steam pipe 3. In the lower end of said body is an oil chamber 4, to which oil is fed through an oil 40 pipe 5. In the middle of said device is a chamber 6, into which the steam from the steam chamber 2, is admitted by means of a valve member 7, mounted upon a rod 8.

In said chamber 6, a second chamber 9, is 45 formed, into which oil is admitted from the oil chamber 4, through a valve 10, mounted upon the rod 8, which carries the valve 7. Said rod 8, has a threaded connection with

a sleeve 11, connected with a diaphragm 12, within a diaphragm casing 13. Mounted above the diaphragm casing is a spring casing 14, within which is mounted a coil spring 15, which rests at its lower end upon the diaphragm 12, above the sleeve 11, and at 50 its upper end said spring is provided with

a plate 16, controlled by a set screw 17, in the upper end of the casing 14, whereby the tension of the spring 15, downwardly upon the diaphragm 12, can be regulated. 60 A steam pipe 18, is connected with the middle portion of the body 1, and is in open communication with the chamber 6, formed therein, as clearly illustrated, whereby steam from the chamber 2, admitted by the valve 65 7, to said chamber 6, passes into said pipe 18, and to the oil burner. An oil pipe 19, is mounted within the steam pipe 18, and is connected through the chamber 6, with the chamber 9, into which the oil passes from 70 the chamber 4, under the control of the valve 10. A steam pipe 20, is inserted through the wall of the body 1, and into the chamber 9, with its end positioned to discharge steam into the open end of the oil 75 pipe 19, as clearly illustrated, said pipe 20, being connected in any desired manner with the steam pipe 3, as by means of a by-pass pipe 21. This steam pipe 20, also affords an outlet for an operating rod 22, which extends through the device, through the oil 80 pipe 19, to the oil burner 23, in which it is connected to the end valve 24, for regulating the discharge from the oil burner. As the oil burner forms no part of this invention it 85 is not shown in detail. The valve rod 8, is constructed at its lower end, as at 8^a, to receive a wrench or other tool, whereby it can be turned into or out of the sleeve 11, for the purpose of moving the valves 7 and 90 10, toward or away from their seats, in the control of steam and oil from the chambers 2 and 4, to the chambers 6 and 9, respectively. Connected with the diaphragm casing 13, is a pressure pipe 25. This pipe is 95 extended to and connected with the boiler, whereby the steam pressure within the boiler is transmitted into the diaphragm casing 13, underneath the diaphragm 12. This pressure operates to flex the diaphragm 12, 100 upwardly against the tension of the spring 15, and in doing so moves the valve members 7 and 10, into their respective seats, and cuts off the steam supply and the oil supply, in a manner which will be very 105 clear from the drawings. When the steam pressure in the boiler lowers to such an extent that the tension of the spring flexes the diaphragm 12, downwardly, it opens the valves 7 and 10, and again admits oil and 110 steam to their respective pipes. Thus, it will be seen that the device operates auto-

matically under the control of the steam in the boiler to supply steam and oil for fuel purposes. By regulating the tension of the spring 15, by means of the adjustment screw 17, and by adjusting the positions of the valves 7 and 10, relative to their valve seats, by turning the rod 8, inwardly or outwardly, as may be required, a very nice and a very accurate adjustment can be had, and a very efficient automatic regulation of steam and oil secured.

I am aware that changes and details can be made in the invention as here illustrated without departing from the spirit thereof, and I do not, therefore, limit the invention to this particular showing, except as I may be limited by the hereto appended claims.

I claim:

1. In a device of the character referred to, in combination with a steam boiler and an oil burner therefor, a casing provided with oil and steam chambers therein with supply pipes leading thereto, respectively, oil and steam pipes from said chambers, respectively, to said oil burner, means for controlling the flow of oil and steam from their respective chambers to said burner, and a steam pipe projected into the oil chamber and positioned for discharging steam at will through the oil pipe leading from the oil chamber to the burner.

2. In a device of the character referred to, in combination with a steam boiler and an oil burner therefor, a casing provided with oil and steam chambers therein, with supply pipes leading thereto, respectively, oil and steam pipes from said chambers, respectively, to said oil burner, valve members for controlling the admission of oil and steam, respectively, to said oil and steam pipes, a diaphragm casing with diaphragm therein, operating connections from said diaphragm to both of said valve members, pipe connections from said boiler to said diaphragm casing, whereby steam pressure from said boiler operates to move said diaphragm and simultaneously operates said valve members, a spring operating on said diaphragm in opposition to said steam pressure, and a steam pipe connection into said casing and adapted to discharge steam at will into the oil pipe leading therefrom to said oil burner, substantially as described.

3. In a device of the character referred to, a casing having oil and steam chambers therein with supply pipes leading thereto, discharge pipes leading therefrom, valve members in said casing connected together and movable to control the oil and steam

supply to said discharge pipes, means for automatically and simultaneously moving said valve members in the control of the oil and steam supply to said discharge pipes, and a steam pipe inserted into said casing in position to discharge steam into the oil discharge pipe, at will, substantially as described.

4. An automatic feed control for oil burners, comprising a casing provided with a steam chamber with steam supply pipe connected thereto, an oil chamber with oil supply pipe connected thereto, a second steam chamber with discharge pipe therefrom with a valve-controlled communication between said steam chambers, a second oil chamber with discharge pipe therefrom and valve-controlled communication between said oil chambers, a steam discharge pipe inserted through said second steam and oil chambers and positioned to discharge steam into the oil discharge pipe leading from said second oil chamber, a steam-pressure-operated device connected with said valves, and means for supplying steam under pressure thereto, whereby to automatically move both of said valves for controlling the passage of oil and steam to the respective discharge pipes, substantially as described.

5. An automatic feed control for oil burners, comprising a casing provided with a steam chamber with steam supply pipe connected thereto, an oil chamber with oil supply pipe connected thereto, a second steam chamber with discharge pipe therefrom with a valve-controlled communication between said steam chambers, a second oil chamber with discharge pipe therefrom and valve-controlled communication between said oil chambers, a steam discharge pipe inserted through said second steam and oil chambers and positioned to discharge steam into the oil discharge pipe leading from said second oil chamber, a steam-pressure-operated device connected with said valves, means for supplying steam under pressure thereto, whereby to automatically and simultaneously move said valves for controlling the passage of oil and steam to the respective discharge pipes, and a spring with means for regulating the tension thereof, operating in opposition to the steam pressure in said device, substantially as described.

Signed at Portland, Multnomah county, Oregon, this 8th day of June, 1916.

JOSEPH L. HOFFMAN.
